(21) Appl. No.: **29/376,087**

(57) **CLAIM**

(22) Filed: **Oct. 1, 2010**

The ornamental design for a hangable air freshening device, as shown and described.

(51) LOC (9) Cl. **28-99**

DESCRIPTION

(52) U.S. Cl. **D23/366**

(58) **Field of Classification Search** D23/355-369;
D28/5, 6; 261/DIG. 17, DIG. 42, DIG. 65,
261/DIG. 88, DIG. 89; 392/386, 390, 391,
392/392, 393, 394, 395; 239/34, 35, 44-47,
239/50, 53, 56, 60, 145, 326

FIG. 1 is a perspective view of a hangable air freshening device showing this new design;

See application file for complete search history.

FIG. 2 is a front view of a hangable air freshening device according to this specification;

FIG. 3 is a rear view of a hangable air freshening device according to this specification;

FIG. 4 is a left enlarged view of a hangable air freshening device according to this specification;

FIG. 5 is a right enlarged view of a hangable air freshening device according to this specification;

FIG. 6 is a top plane view of a hangable air freshening device according to this specification; and,

FIG. 7 is a bottom plane view of a hangable air freshening device according to this specification.
